RETENTION SUTURE BRIDGE

Ingram S. Chodorow, New York, N.Y., assignor to
Technalytics Incorporated, New York, N.Y.

Filed June 3, 1970, Ser. No. 23,284

Term of patent 14 years

Int. Cl. D24—05
U.S. Cl. D83—12

FIG. 1

FIG. 4 FIG. 5

FIG. 2

FIG. 3

FIG. 6

FIG. 7

FIG. 1 is a front elevational view of the retention suture bridge (the rear elevation view is substantially identical),

FIG. 2 is a top plan view thereof,

FIG. 3 is a bottom plan view thereof,

FIGS. 4 and 5 are end views thereof, and

FIGS. 6 and 7 are bottom and top perspective views.

I claim:

The ornamental design for a retention suture bridge, as shown and described.
